FLASHLIGHT

William M. Lennan, Pasadena, Calif.

Application March 14, 1936, Serial No. 68,865

12 Claims. (Cl. 240—10.69)

This invention relates to improvements in flashlights.

The general object of the invention is to provide an improved flashlight including batteries, an electric light, and an electric control switch, all of which are enclosed in a fluid proof housing.

Another object of the invention is to provide a flashlight including novel means for mounting the electric light bulb socket.

10 A further object of the invention is to provide a flashlight including novel means for electrically connecting the electric light bulb socket to the batteries.

15 A still further object of the invention is to provide a flashlight including novel means for obtaining the correct focus between the electric light bulb and the light reflector.

Other objects and the advantages of this invention will be apparent from the following description taken in connection with the accompanying drawing, wherein:

Fig. 1 is a longitudinal section through my improved flashlight;

Fig. 2 is a section of the flashlight taken on line 2—2 of Fig. 1;

Fig. 3 is a section taken on line 3—3 of Fig. 1;

Fig. 4 is a view of the rear end of the metal casing;

Fig. 5 is a side elevation of the flashlight casing removed from the rubber housing;

Fig. 6 is a fragmentary, sectional view showing a flashlight with the exterior operated focusing means omitted; and

Fig. 7 is a section taken on line 7—7 of Fig. 1.

35 Referring to the drawing by reference characters I have indicated my improved flashlight generally at 10. As shown the flashlight 10 includes an outer water-tight or fluid proof housing 12 and an inner casing 13 removably associated with said housing. As best shown in Fig. 5, the casing and the parts secured thereto (hereinafter called the casing and designated by the reference character 13) comprise a unit independent of and preferably separable from said

40 housing. This casing includes a support comprising a semi-cylindrical shell 14 which is open at both ends and is preferably made of metal, such as aluminum. At the rear of the shell 14 an annular cup-shaped disk 15 is provided which is preferably made of aluminum. The disk 15

45 may be secured to the shell 14 by a plurality of fingers 16 which are integral with the shell and extend through suitable apertures in the disk 15 and are then bent over to engage the outer face 50 of the disk. (See Fig. 4.)

At the front of the shell 14 an annular cup-shaped aluminum disk 17 is provided which may be secured to the shell 14 in the same manner as the disk 15.

Mounted on the disk 15 I provide a flat spring 5 member 18 which is bent back upon itself to form two arm portions 19 and 20 with the arm 19 engaging the inner face of the disk 15. To secure the spring 18 to the disk 15 I provide a stirrup member 21 which is positioned over the spring arm 19 and includes lip members 22 which extend through an aperture 23 in the disk 15 and engage the rear surface of the disk. (See Figs. 1, 4, and 5.)

The front casing disk 17 has an aperture 24 therethrough. Positioned against the inner surface of the disk 17 I provide a disk 25, and positioned against the outer surface of the disk 17 I provide a disk 26. Both the disks 25 and 26 are made of an electrically insulating material such as hard rubber or fiber. Positioned against the rear surface of the disk 25 I provide a metal plate 27 and positioned forward of the disk 26 I provide a metal reflector guard 28. The reflector guard 28 is frusto-conical or cup-shaped and includes side walls 29 and a bottom wall 30 which is positioned against the forward surface of the disk 26.

The disks 25 and 26, the plate 27, and the bottom wall 30 of the reflector guard are all apertured as indicated at 31 concentric with the aperture 24 in the disk 17. Positioned in the apertures 31 and the aperture 24 I provide an externally threaded sleeve 32 which includes an enlarged head 33 and has a threaded aperture 34 therethrough. The aperture 24 is of such a size that the disk 17 is free from engagement with the sleeve 32. As shown the sleeve head 33 engages the inner surface of the plate 27 and a nut 35 on the sleeve 32 engages the bottom wall 30 of the reflector guard. Positioned between the disk 26 and the bottom wall 30 of the reflector guard 28 I provide a contact ring 37 including a contact finger 38 which extends forwardly over the reflector guard. When the nut 35 is tightened up the bottom wall 30 of the reflector guard, the contact ring 37, the disk 26, the disk 17, the disk 25, and the plate 27 are firmly clamped between the sleeve head 33 and the nut 35.

Mounted on the casing shell 14 in line with the contact finger 38 of the contact ring 37 I provide a switch device or mechanism indicated generally at 40. As shown the switch mechanism 40 includes an open-topped U-shaped metal box 41 which may be secured to the shell 14 in any

desired manner and in the side walls has two pair of opposed apertures 42 and 43. (See Fig. 5.)

5 Positioned in the box 41 I provide an operating member 44 and a latch member 45. As shown the operating member 44 is made of metal and includes spaced downwardly extending side walls 46, each of which intermediate the length of the operating member has an outstruck trunnion 10 member 47 thereon which is positioned in the corresponding aperture 42 in the box 41. The latch member 45, like the operating member 44, is made of metal and includes spaced downwardly extending side walls 48 which have outstruck 15 trunnion members 49 thereon positioned in the casing apertures 43.

The forward end 50 of the operating member 44 overlies the contact finger 38 and is normally spaced thereabove as shown in Fig. 1. The rear 20 end 51 of the operating member 44 is normally positioned below the forward end 52 of the latch member 45. A flat spring 53 is positioned in the box 41 below the members 44 and 45 and includes upturned end portions, one of which 25 engages the forward portion of the operating member 44 and the other of which engages the rearward portion of the latch member 45 and retains the operating and latch members in the previously described normal position.

30 Positioned in the threaded aperture 34 of the sleeve 32 I provide a metal stud 54 which forms part of the lamp-supporting member. Positioned against the rear face of the stud 54 I provide a circular fiber disk 55, the peripheral edge of 35 which is toothed as indicated at 56 in Fig. 3. The disk 55 and the stud 54 are connected for unitary rotation by a plurality of key pins which are integral with the stud and are positioned in suitable apertures in the disk 55, as indicated at 40 57. Opposite the disk 55 the stud 54 has a threaded recess 58 therein in which the base of an electric light bulb 59 is adapted to be positioned.

Positioned in the recess 58 I provide a rubber washer 60. When the bulb 59 is operatively positioned in the socket 58 the rubber washer 60 in the socket is compressed between the bottom of the socket and the end of the bulb. When the washer 60 is thus compressed, pressure is applied to the end of the bulb which prevents the bulb 50 from accidentally unscrewing. The stud 54 further includes a concentric aperture 61 which at one end opens into the recess 58 and at the opposite end opens through the rear face of the stud. The stud 54 has a plurality of longitudinally extending slits 62 therein which extend from the end opposite the disk 55 a predetermined distance toward the disk 55. These slits 62 allow the side walls of the stud to spring radially outwardly to apply friction between the stud and the sleeve 32 60 to thereby prevent accidental rotation of the stud 54.

Positioned in the aperture 61 I provide a hollow fiber sleeve 63 and in the bottom of the recess 58 I provide a fiber washer 64. The disk 55 is 65 shown as secured to the stud 54 by a rivet 65, one end of which forms a center contact for the bulb in the recess 58 and the opposite end of which forms a battery contact portion 66.

A cup-shaped reflector member 67 having an 70 aperture 68 in the bottom thereof is provided with an outer edge which is curved back upon itself to form a rearwardly extending flange 69 which fits over the outer edge of the reflector guard 28, so that the light reflector 67 is removably 75 supported by said guard. The transparent clo-

sure member 82 is pressed against the front edge of the reflector 67 by the flexible rubber housing and normally holds the reflector in place; the flange 69 of the reflector being clamped between the transparent closure 82 and the reflector guard 28. The electric light bulb 59 is positioned in the aperture 68 of the reflector 67.

Mounted on the plate 27 adjacent each side of the toothed disk 55 I provide reciprocable actuating members or plungers such as bar members 70, both of which are slidably positioned in bearing portions 71 on the plate 27. Each of the bars 70 has a rearwardly extending finger portion 72 thereon which is adapted to engage the teeth 56 of the disk 55. Adjacent the lower ends 15 of the bars 70 I provide a cross bar 73 which is pivotally secured intermediate its length to the plate 27 as at 74. Adjacent each end the cross bar 73 is loosely connected to the bar members 70 as at 75.

When one of the bars 70 is moved upward the other bar 70 moves downward and finger portion 72 of the upwardly moved bar 70 engages a tooth 56 of the disk 55 and rotates the disk 55 in one direction, a tooth at a time.

A spring member 76 may be mounted on the plate 27 to coact with the cross bar 73 to retain the bars 70 in a normal position and to return them to a normal position when they are released after being moved.

The fluid proof or water-tight housing 12 is made of a good grade of somewhat flexible rubber and includes a hollow cylindrical portion 77, one end of which is closed by integral wall 78. The opposite end of the housing 12 is flared outwardly to form an enlarged end portion 79 which is open ended. Extending inward from the inner surface of the flared portion 79 I provide a plurality of spaced boss members 80. (See Figs. 1 and 2.) One end side of the housing 12 includes 40 an integral raised portion 81 in which a chamber 82 is provided which communicates with the interior cylindrical portion and the enlarged end portion. Opposite the raised portion 81 the housing 12 includes an integral raised portion 83 in 45 which a chamber 84 is provided which communicates with the interior of the cylindrical portion and the enlarged portion.

The casing 13 is positioned in the housing 12 with the shell 14 positioned in the cylindrical 50 portion 77 of the housing and the reflector guard 28 positioned in the enlarged end portion 79. When the casing member 13 is operatively positioned in the housing 12 the members 80 of the housing engage the outer surface of the reflector 55 guard 28. (See Fig. 2.)

The switch mechanism 40 is positioned in the chamber 82 of the raised portion 81 and the focusing mechanism is positioned in the chamber 84 of the raised portion 83.

In the upper surface the raised portion 81 includes a pair of recesses 85 and 86, the bottom wall of which is curved upwardly to form button portions 87 and 88, respectively. The button portion 87 is located over the forward end of the operating member 44 of the switch 40 and the button 88 is located over the rear portion of the latch member 45.

The under face of the enlarged portion 83 has a pair of recesses 89 therein, the bottom walls of 70 which are curved downwardly to form button portions 90. The button portions 90 are located one below each of the bar members 70.

In the interior surface of the enlarged portion 78 adjacent the open end thereof I provide an 75

annular recess 91 which is adapted to receive a closure or lens member 92. The lens member 92 is preferably made from a non-fracturable, fire-proof, transparent material, such as "Plastic".

In operation a standard set or battery of dry cells 93, one pole of which is formed by the bottom of the metal casing and the other pole by a center contact member 94, is positioned in the shell 14 between the disk 15 and the disk 17. The cells are positioned in the shell 14 with the bottom thereof engaging the spring 18 and with the top center contact thereof engaging the rivet portion 66, as shown in Fig. 1.

To light the bulb 59, inward pressure is applied to the housing by moderate pressure applied on the button member 87. When predetermined pressure is applied at 87 the end portion 50 of the operating member 44 moves downward against the action of the spring 53 into engagement with the spring contact finger 38, whereupon current flows from the center contact 94 of the battery 93 through the rivet 65 to the center contact of the bulb 59, thence through the filament and the base thereof and through the stud 54 and the sleeve 32 to the contact member 38 and returns to the battery through the switch device 40 and the casing 13.

When a greater pressure is applied to the button 87, the end 51 of the arm 44 raises above the end 52 of the latch member 45 and then when the pressure is removed the latch member 45 retains the end 51 of the arm 44 raised, as shown in Fig. 5, thus retaining the end 50 of the operating arm 44 in engagement with the contact finger 38. To release the operating member 44 inward pressure is applied to the housing, thus moving the button portion 88 inward. When pressure is applied to move the button 88, the forward end 52 of the latch member 45 moves out from under the end 51 of the arm 44, whereupon the spring 53 moves the operative member to its initial position, whereupon the end 50 of the operating member moves out of engagement with the contact finger 38.

To rotate the disk 55 when the casing 13 is operatively positioned in the housing 12, inward pressure is applied to the housing by pressing one of the buttons 90 inward so that the inner surface of the housing engages the adjacent bar member 70, whereupon further inward movement of the button moves the bar 70 inward and the finger portion 72 thereof rotates the disk teeth 56 as previously described. As the disk 55 is rotated, it rotates the stud 54 and lamp 59 and, due to the threaded connection 34 between the sleeve 32 and the stud 54, the lamp 59 is moved or shifted either toward or away from the reflector holder 28 and the reflector 67, depending on which way the disk 55 is rotated.

In Fig. 6 I have indicated a slightly modified form of the flashlight shown in Figures 1 to 5 and 7, this embodiment being designated generally as 100. This modified embodiment is similar in all respects to the flashlight shown in Figs. 1 to 5 and 7 except that the plate 27 is omitted and a washer 101 substituted therefor and the housing 12' does not include the enlarged portion 83 and the chamber 84. With the flashlight shown in Fig. 6 it is necessary to remove the casing 13' from the housing 12' in order to focus the bulb in relation to the lens.

From the foregoing description it will be apparent that I have provided a novel flashlight

which is simple in construction and highly efficient in use.

Having thus described my invention I claim:

1. In a flashlight, a casing; an internally threaded member fixed to said casing; a reflector operatively connected to said member in fixed position relative thereto; an externally threaded lamp bulb support engaging the threads of said member; a toothed member secured to said bulb support; and a pair of separately movable actuating members mounted on said casing to engage said toothed member upon movement to rotate the same and thereby move said bulb supporting means relatively to said reflector.

2. A flashlight as claimed in claim 1 provided with a hollow flexible housing, the ends of said actuating members opposite said toothed member terminating adjacent the interior of said flexible housing.

3. In a flashlight, a hollow housing having a transparent member at one end thereof, means to movably support an electric bulb socket in said housing, said means including relatively rotatable threaded coating members, means to support a light reflector member in said housing, and means including a pair of plungers operable from the exterior of the housing to rotate one of said threaded coating members and to thereby move said socket relative to said reflector.

4. A flashlight comprising a flexible watertight rubber housing having an open portion and having a transparent closure for said open portion and a casing member in said housing, said casing member comprising a unit independent of said housing and closure and including a support having an electric bulb socket mounted thereon at one end and having a reflector guard thereon disposed about said socket, a reflector within said guard, and means to engage a battery and mounted on the support at the end thereof opposite said socket, a circuit closing member associated with said socket, and means mounted on said support to operate said circuit closing member.

5. In a flashlight, a hollow flexible housing open at one end and closed at the opposite end, a transparent member, said housing including means adjacent said open end to removably support said transparent member to close said open end, a casing in said housing, a reflector mounted in said housing, a threaded member secured in fixed position on said casing, said reflector having an aperture therein, a second threaded member engaging said first threaded member, an electric light bulb socket on said second threaded member, an electric light bulb associated with said socket and extending through said aperture, and means to turn said second threaded member to shift said socket relative to said reflector.

6. In a flashlight, a hollow housing open at one end and closed at the opposite end, a transparent member, said housing including means adjacent said open end to removably support said transparent member to close said open end, a casing in said housing, said casing including a shell having a threaded member thereon, a bulb socket mounted on said member, a toothed disk on said threaded member, and a pair of plungers movably mounted, said plungers including means to engage the teeth of said toothed disk to rotate said toothed disk and shift said bulb socket.

7. In a flashlight, a hollow flexible housing open at one end and closed at the opposite end, a transparent member, said housing including means adjacent said open end to removably support said transparent member to close said open end, a rigid

casing in said housing, said casing including a semi-cylindrical shell having a disk thereon at each end, a cup-shaped reflector guard mounted on said disk at one end of said shell, a reflector engaging said guard, a spring member mounted on said disk at the opposite end of said shell, an internally threaded sleeve mounted on said first disk, an externally threaded stud positioned in said sleeve, a bulb socket mounted on said stud, a toothed disk secured to said stud in said shell, a plate mounted on said first disk, a pair of plungers movably mounted on said plate, said plungers including means to engage the teeth of said toothed disk to rotate said toothed disk.

15. 8. In a flashlight, a hollow flexible housing open at one end and closed at the opposite end, a transparent member, said housing including means adjacent said open end to removably support said transparent member to close said open end, a casing in said housing, said casing including a semi-cylindrical shell having a disk thereon at each end, a cup-shaped reflector guard mounted on said disk at one end of said shell, an internally threaded sleeve mounted on said first disk, an externally threaded stud positioned in said sleeve, a cup-shaped light reflector removably supported by said guard, said reflector having an aperture therein, a toothed disk secured to said stud in said shell, a threaded recess in said stud with the open end thereof opposite said toothed disk, said threaded recess forming an electric light bulb socket, a center contact member for said socket mounted on and insulated from said stud, an electric light bulb positioned in said socket and extending through said reflector aperture, a plate member mounted on said first disk, a pair of plungers movably mounted on said plate, said plungers including means to engage the teeth of said toothed disk to rotate said toothed disk.

25. 9. In a flashlight, a hollow flexible housing closed at one end, a casing within said housing, a reflector member and a lamp supporting member forwardly of said casing, one of said members being secured to said casing by a screw-threaded means and being provided with a toothed disc, and focusing means comprising a pair of plungers to engage said toothed disc to rotate the same whereby said reflector member and supporting member are moved relatively to each other.

30. 10. In a flashlight, a hollow housing closed at one end, a casing within said housing, a reflector member and a lamp supporting member forwardly of said casing, one of said members being secured to said casing by a screw-threaded means and being provided with a toothed disc, and focusing means comprising a pair of plungers to engage said toothed disc to rotate the same whereby said reflector member and supporting member are moved relatively to each other.

35. 11. A flashlight comprising a flexible watertight rubber housing having an open end, a transparent closure removably secured therein, a support disposed within said housing and removable therefrom, said support comprising a shell and a reflector guard, said shell and said guard both internally supporting said housing, and a switch mounted on said support, said housing having a raised portion providing a chamber within which said switch is positioned, said raised portion having a resilient part opposite said switch adapted to be pressed inwardly to operate said switch.

40. 12. A flashlight comprising a flexible watertight rubber housing means closed at one end, a metal casing disposed within said housing means, a forward disk member carried by said casing, a lamp bulb socket operatively connected to said disk member, a substantially frusto-conical reflector guard having its smaller end connected in fixed relation to said disk member, a reflector within said reflector guard and provided with an outer edge which is curved back upon itself to form a rearwardly extending flange which fits removably over the front edge of said reflector guard, and water-tight means, including a transparent closure member removably secured adjacent the end of said housing means opposite said closed end and pressing against said flange, to hold said reflector in place within said guard and to retain said reflector, guard and casing in assembled relation within said housing means.

45. contact member for said socket, said center contact member being mounted on and insulated from said stud, an electric light bulb positioned in said socket and extending through said reflector aperture, a plate mounted on said disk, a pair of plungers movably mounted on said plate, said plungers including means to engage the teeth of said toothed disk to rotate said toothed disk, a battery positioned in said shell, a contact finger electrically connected to said stud, means to conduct current from said battery to said contact finger and to said center contact member, said means including a switch device, said casing being positioned in said housing with the open end of said light reflector towards said transparent member, means whereby said switch device is actuated to operative and inoperative positions by pressure being applied to predetermined areas of said housing, and means whereby said plungers are movable to rotate said toothed disk by pressure applied to predetermined areas of said housing.

50. 13. A flashlight comprising a flexible watertight rubber housing having an open end, a transparent closure removably secured therein, a support disposed within said housing and removable therefrom, said support comprising a shell and a reflector guard, said shell and said guard both internally supporting said housing, and a switch mounted on said support, said housing having a raised portion providing a chamber within which said switch is positioned, said raised portion having a resilient part opposite said switch adapted to be pressed inwardly to operate said switch.

55. 14. A flashlight comprising a flexible watertight rubber housing means closed at one end, a metal casing disposed within said housing means, a forward disk member carried by said casing, a lamp bulb socket operatively connected to said disk member, a substantially frusto-conical reflector guard having its smaller end connected in fixed relation to said disk member, a reflector within said reflector guard and provided with an outer edge which is curved back upon itself to form a rearwardly extending flange which fits removably over the front edge of said reflector guard, and water-tight means, including a transparent closure member removably secured adjacent the end of said housing means opposite said closed end and pressing against said flange, to hold said reflector in place within said guard and to retain said reflector, guard and casing in assembled relation within said housing means.

60. WILLIAM M. LENNAN.
